Company, Norwood, Ohio, a corporation of
Ohio

Application November 30, 1934, Serial No. 765,273

2 Claims. (Cl. 172—126)

The present invention relates to improvements in the construction of magnetic motors of the oscillatory type and has for its object to produce a simplified construction which will be durable and dependable in its operation and which will moreover be operable with the minimum requirement of electrical energy thereby to adapt it for economical operation over extended periods by battery current.

Important features of the present invention which contribute to the economical operation of my improved device consists in the employment, as the actuator or impeller member, of a pivotally supported arm carrying at its lower end a magnet coil operative as a pendulum weight and cooperating with a fixed armature rod curved to conform to the path of movement of the coil combined with a make and break control switch of improved type adapted periodically and for a short interval only to energize the coil for producing an impelling impulse to the pendulum actuator sufficient for maintaining the continued oscillation thereof. The improved control switch is of a type employing a rotary contact member preferably of ratchet formation rigidly supported and arranged to co-act with a pawl contact member carried by the oscillating arm for imparting a progressive advance movement to the rotary member at each stroke of the actuator; the arrangement providing for closing of the circuit once for each given number of strokes of the pendulum actuator as determined by the switch formation. There is thus provided a plural oscillation with relation to the power impulses resulting in a prime mover particularly well adapted for operating advertising displays of light load with the minimum of current consumption.

The described and other important features and advantages of the present improvements will be more fully understood by reference to the accompanying drawing wherein like reference characters are applied to the corresponding parts in the several views.

45 In the drawing:

Fig. 1 is a view in front elevation showing my improved motor construction.

Fig. 2 is a partly sectional view thereof in side elevation.

50 Fig. 3 is an enlarged detail view taken in rear elevation of the switch contact members.

Fig. 4 is a partly sectional view thereof in side elevation.

55 Fig. 5 is a detail sectional view showing the insulated support for the control switch bracket.

In the approved embodiments of the features of the present invention as here shown, the improved oscillatory motor is designed to be adapted for operating animated advertising displays and comprises a supporting member or bracket 5 1 of angle form adapted to be rigidly secured to a panel or other member of an advertising display having movable parts to be operated by the motor. The upper portion of the bracket has a reversely bent end portion 2 suitably spaced 10 from the bracket main portion to receive oppositely positioned bearing pins 3—3 threaded in the bracket and secured by clamping nuts as shown in Fig. 2. The pins have tapered inner ends forming a pivotal bearing for the actuator 15 or impeller arm 4 formed at its lower end with a loop 5 to which is fitted the electromagnetic coil 6 having a central longitudinal opening therethrough for the reception of a co-acting armature member. The coil 6 is accordingly carried 20 by the pivotally supported actuator arm to act as a pendulum weight therefor. The upper end of the actuator arm is extended above the pivot as shown and perforated for pivotal connection with a connection to the movable parts to be actuated 25 thereby.

An armature or core rod for co-action with the coil is provided in the form of a curved soft iron rod 8 rigidly mounted on the bracket 1 and curved to conform to the path of movement of the coil and centrally aligned with the coil opening to allow of the latter swinging freely thereover. The core 8 is of a length as shown to extend partially within the coil when the actuating arm is in vertical or rest position. 35

In its operation the coil is energized from a suitable electric circuit intermittently to impart a power impulse to the actuator arm in one direction of its movement or swing. In accordance with the present invention a control switch closes 40 the circuit periodically in the swing of the actuator arm in the power direction which is toward the right as shown in Fig. 1. To this end the control switch is arranged to be operated by the movement of the actuator arm and is designed 45 to effect closing of the circuit once for each given number of strokes of the actuator arm; the timing as here provided for giving a closing of the circuit by power impulse during each third swing toward the right with two intervening non-power 50 strokes.

To be so operative, a rotary ratchet and pawl actuated switch is employed consisting of a rotary member 10 of insulating material having a series of peripheral ratchet teeth 11 and jour- 55

nalled upon a bearing stud 12 carried by an insulated bracket 14 rigidly secured to but insulated from the bracket member 4. The rotary ratchet member 16 is positioned to be engaged by a metal pawl 18 pivotally supported on a stud 17 carried by the actuator arm 4 and insulated therefrom. Associated with the pawl mounting there is a stop plate 19 having a stop shoulder 19 to oppose swinging of the pawl in one direction. Accordingly, the swinging of the actuator arm will effect the advance rotation of the ratchet member 16 the distance of one tooth for each swing or stroke of the actuator arm toward the right as shown in Fig. 1.

For periodic closing of the circuit, the rotatable ratchet member has mounted thereon a metallic terminal member having radially positioned contact portions 21 oppositely arranged to provide facings for the front or radially disposed portions of opposite teeth of the ratchet member as best shown in Figs. 3 and 4. The terminal member 20 also has a cylindrical or hub portion 22 surrounding the hub portion of the ratchet member. This cylindrical portion 22 is engaged by a spring clip or brush 24 of a terminal plate 20 secured on the metal bracket 14. A lead 21 from a battery, or other source of electrical energy, is connected by screw 26 to the arm 14 through which the current passes to the terminal plate 28 having constant brush engagement with switch terminal 22 from which the circuit is periodically closed to the coil upon engagement of the pawl with the contact portions 21 at which time the current flows through the pawl, its fulcrum stub 17 to wire 30, thence through the coil 6 and connection 31 to bracket 4; the latter being grounded by connection 32 (Fig. 2).

As shown best in Fig. 5, the bracket 14 is supported to be insulated from the bracket 4 by the insulating plate 33 and insulating bushings 34-35. As shown in Fig. 4, the pawl 18 is likewise mounted or supported on the actuating arm to be insulated therefrom by insulating plate 36 and bushings 37-38.

In operation, my improved oscillatory motor will produce a magnetic impulse periodically in the movement of the pendulum acting actuator arm in one direction, every third stroke in the embodiment as illustrated, and this impulse occurs only during the interval of the engagement of the pawl with the contact ratchet teeth. Accordingly for light load operation of the motor a minimum of current is used thereby adapting the motor for battery current use for extended periods of operation.

While I have shown and described an approved embodiment of the features of my invention, it will be understood that varied modifications may be made therein without departing from the scope of the invention as defined in the 5 appended claims.

Having described my invention, I claim:

1. An oscillatory motor of the character described comprising a supporting member, a pendulum acting actuator arm pivotally supported thereon, an actuating magnet and armature arranged for imparting an impelling force to the actuating arm, a rotary switch member of insulating material journalled on the supporting member and formed with ratchet teeth, 15 a pawl pivoted upon the arm to engage the ratchet teeth, a shouldered member to oppose swinging of the pawl in one direction, a terminal member carried by the switch member, said terminal member having a cylindrical portion 20 and radially disposed contact portions providing faces for certain of the ratchet teeth, a brush contact member on the supporting member engaging the terminal cylindrical portion and circuit closing connections to the brush contact 25 member and from the pawl to the coil whereby the latter will receive an impelling force during the period of pawl engagement with the contact portions of the switch terminal member to effect closing of the magnet circuit periodically with 30 intervening non-circuit closing movements of the switch member.

2. An oscillatory motor of the character described comprising a supporting member, a pendulum acting actuator arm pivotally supported thereon, an actuating magnet for operating the arm comprising a coil supported upon the arm at its lower end, a fixed armature to co-operate therewith having a portion curved to conform to the path of movement of the coil, a 40 rotary switch member of insulating material journalled on the supporting member and formed with ratchet teeth, a pawl pivoted on the arm to engage the ratchet teeth, a terminal member carried by the switch member and having a cylindrical portion and contact portions providing faces for certain of the ratchet teeth, a brush contact member on the supporting member engaging the cylindrical portion and circuit closing connections to the brush contact 45 member and pawl for closing the circuit through the coil.

JOHN G. RUCKELHAUS.
